WRENCH FOR ELECTRICAL CONNECTOR PLUGS OR THE LIKE

Albert G. Fink, 515 W. Beverly Drive, Whittier, Calif.

Filed Nov. 17, 1961, Ser. No. 67,573

Term of patent 14 years

(Cl. D54—16)

Fig. 1

Fig. 2

Fig. 3

Fig. 4

FIGURE 1 is a top plan view of a wrench for electrical connector plugs or the like, showing my new design;

FIGURE 2 is a front elevational view thereof;

FIGURE 3 is a bottom plan view thereof; and

FIGURE 4 is a rear elevational view thereof, illustrated as though it were a front elevational view of the article in its aspect shown in FIGURE 3.

I claim:

The ornamental design for a wrench for electrical connector plug or the like, substantially as shown.
